UNITED STATES PATENT OFFICE.

WILLIAM WERNER, OF MEXIA, TEXAS.

MULTIPLE-STAGE PUMP.

Application filed March 19, 1926. Serial No. 95,815.

My invention relates to pumps and particularly to pumps adapted to be employed in deep well work. It is not confined to this particular use, however, as will more clearly appear hereinafter.

It is frequently desirable to raise liquid from deep wells through a pump adapted to reciprocate with only a short stroke. The difficulty, however, with pumps in which the plunger moves through only a short distance on each stroke is that the capacity of the pump is thereby exceedingly limited and will necessitate the rapid reciprocation of a pump rod in order to produce adequate results. There is a limit, however, on the speed with which a pump rod can be run safely and economically, and it is an object of my invention to provide a pump of large capacity and adapted to be operated on a short stroke of the pump rod. In order to do this, I contemplate the provision of a multiple piston pump which will be described in detail in the specification which follows. It is an object of the invention to provide a multiple stage pump which may be constructed cheaply and operated efficiently in all depths of wells.

The invention resides particularly in the general construction and arrangement of the parts making up my improved device, for an understanding of which reference is made to the accompanying drawings in which Fig. 1 is a central vertical section of a well casing or screen having my pump arranged therein, illustrating the upper portion of the pump mechanism, and Fig. 2 illustrating the lower end thereof. Figs. 3 and 4 are sections similar to Figs. 1 and 2 but drawn in section at approximately right angles to the sections shown in Figs. 1 and 2. Figs. 5, 6 and 7 are transverse sections on the lines 5—5, 6—6 and 7—7, respectively, of Figs. 1, 3 and 4. Fig. 8 is a transverse section on the line 8—8 of Fig. 2. Fig. 9 is a similar section on the line 9—9 of Fig. 2, and Fig. 10 is a similar section on the line 10—10 of Fig. 2. Like numerals of reference are employed to designate like parts in all the views. In the drawing, I have illustrated my pump as being set within a strainer 1 of a well, said strainer comprising a pipe having openings 2 therein to admit the fluid from the well to the interior of the casing, where it may be received by the pump.

The pump is secured at the lower end of a tubing 3 of a comparatively large diameter

but adapted to fit freely within the screen. The tubing is threaded at its lower end to engage with a head 4 which comprises a casting threaded to fit within said tubing 60 and being oblong in shape between its ends forming a bearing for a plurality of outlet tubes 5 therethrough. Said tubes are adapted to reciprocate within bearing sleeves 6 fitting within openings longitudinally of the 65 head. Said head is recessed as shown at 7 on one side thereof to provide space for the operation of a valve communicating with the chamber 8 below said head.

Said valve comprises a valve chamber 9 70 screwed within an opening 10 in the lower end of the head 4, as will be seen from Fig. 3. Said valve is placed at the side away from the two reciprocating tubes or plungers 75 5 and 5'. The valve chamber has a lower downwardly flaring seat 11 to receive the head 12 of the valve. A stem 13 on said valve projects upwardly through the valve chamber and has a bearing at 14 within the hub formed at the upper end of the valve cage 80 15 secured to the upper end of the chamber. Above the valve cage the stem 13 is formed with a plate 16 thereon against which a compression spring 17 is adapted to bear, thus holding the valve head 12 resiliently in its 85 seat. It will be noted that this valve opens downwardly into the chamber 8 and when open will allow the passage of fluid from the well into the said chamber.

The head 4 is secured at its lower end to the pipe section 18 of the same diameter as the tubing, said section being connected at its lower end 19 to a second head 20, similar in all respects to the head 4, previously described. The section 18 is of sufficient length 90 to provide a cylinder for the reciprocation of a pump piston 21. Said piston comprises an upper solid head having threaded openings therethrough to allow connection therewith of the two tubes 5 and 5', previously 95 mentioned. The lower end of the piston is hollowed out on its interior, leaving downwardly extending skirt 22 thereon at the lower end of which an outer ring 23 is secured. Between said ring and a shoulder 24 100 at the upper end of the piston a seat is provided for a sleeve 25 of packing material adapted to make a close sliding fit with the interior of the cylinder or pump barrel formed by the pipe section 18.

The tubes 5 and 5' are connected at their upper ends above the head 4 to a valve

block 26. The shape of said block 26 is indicated best in Fig. 5. It has two openings therethrough, indicated at 27, the lower end of said openings being threaded to receive the upper ends of the tubes 5 and 5'. A third opening 28, approximately centrally of the block, is provided to receive the threaded lower end of a pump rod 29, shown in Fig. 3. The upper ends of the two openings 27 are provided with valve seats 30 formed by rings counter sunk in the outer end of said openings and having their upper faces beveled outwardly to form a seat for the ball valves 31 and 32. Said valves are limited in their movement away from the seat, thus provided, by a cage formed by a plurality of posts 33 threaded within the upper end of the block 26 about the said openings and connected with a plate 34 at their upper ends against which the ball valves will contact at the upper limit of their movement.

The tube 5' is slotted on one side at 35 to provide an opening from the chamber 8 into said tube for the entrance of fluid being pumped. The tube 5 has a similar slotted opening 36 on one side thereof below the piston 21 and adapted to communicate with the interior of the chamber 8 below the piston.

The pump may have as many pistons of the construction described as are desired to produce the full volume of fluid desired up to the capacity of the tubing. I have shown two such stages, and in carrying out this construction, the tubes 5 and 5' are extended downwardly through the head 20, previously described, there being packing sleeves 37 through the openings in said head 20 to provide a close sliding fit for said tubes in the same manner as occurs in connection with the packing sleeve 6 in the head 4. Below the head 4 is secured a second pipe section or pump barrel 38 which provides therein a chamber 39 in which a piston 40 is adapted to reciprocate, said piston being secured at the lower ends of the two tubes 5 and 5', previously described. Said piston has packing 41 thereon, as in case of the other piston, said packing resting upon the ring 42 at the lower end of said piston.

The tube 5' is secured within a recess 43 in the upper end of the piston head 40, said recess being closed at its lower end. A slotted opening 44 is provided in the tube 5' leading to the chamber 39 within the pump barrel. The tube 5 is connected in the head of the piston also but a passage 45 is provided through the head of the piston leading to the hollow interior 46 of the piston 40.

The lower end of the pump barrel 38 is closed by means of a plate 47 which acts 65 to support a standing valve for the said

pump. Said valve has a chamber 48 flaring toward its upper end to provide a seat 49 for a valve 50. Said valve is adapted to open upwardly and has a stem 51 with a washer 52 at its lower end against which a spring 53 is adapted to bear in such manner as to hold the standing valve resiliently in its seat. The valve cage 54 supports the upper end of said spring, said cage having openings 55 therein to allow the passage of the fluid.

A standing valve must, of course, be provided for each stage of the pump and the standing valve for the stage first described is positioned immediately below the piston 21 and within the upper end of the head 20. Its construction is shown in Fig. 4 and it will be noted that it is identical with the standing valve just described. It is, however, positioned at one side of the center of the head, as shown particularly in Fig. 6. The valve chamber is designated at 48', the valve head by the numeral 50', and the other parts being numbered as in the case of the lower standing valve. This valve allows the passage of fluid from the well screen upwardly into the chamber below the said upper piston 21.

In the operation of this device, the pump rod 29 is reciprocated from the upper end of the well and in so doing, the upper block 26 and the tubes 5 and 5' secured therein are likewise reciprocated. Considering the lower pump piston first, it will be noted that on the upstroke of the piston 40 fluid will be drawn in from the well past the valve 50 into the pump barrel below said piston, and on the return, or down, stroke of the piston the fluid will be forced upwardly through the tube 5 toward the surface past the valve 31 into the tubing. On the same down stroke, the chamber 39 above the piston will be filled with fluid by way of the valve 9' secured in the lower end of the head 20, said valve 9' being identical in all respects with the valve 9, previously described. The said valve 9' is shown best in Fig. 4 of the drawing.

The chamber 39 being thus filled with fluid, a passage is provided for said fluid when the pump plunger moves upwardly, the said passage being by way of the tube 5'. The fluid finds entrance thereto through the slots 44 in the side thereof, and the upstroke of the piston will force the fluid above said piston upwardly in said tube toward the surface, the valve 32 being forced from its seat by the pressure of said fluid, allowing the fluid to move toward the surface.

A similar action occurs in connection with each stage of the pump. Considering the pump piston 21, the downward movement of the piston will close the standing valve 50' thereof and the fluid below the piston will

be forced into the slots 36 to the tube 5 and thereby be forced upwardly past the valve 31 into the tube. On the downward stroke the fluid will also be drawn into the chamber 8 by way of the valve 12, previously described, so that the chamber 8 will be thereby filled and on the upward stroke of the piston the fluid in the chamber 8 will be forced through the slots 35 into the tube 5' and 10 passed upwardly into the tube.

It will be noted that I have provided two separate stages for my pump, each of which is adapted to operate to force fluid upwardly in the tubing, both on the downward stroke 15 and on the upward stroke of the plunger. The ultimate effect of the operation of the pump shown in the drawing is to produce two upward impulses of fluid in the tubing on each stroke of the plunger. I am thereby 20 enabled to produce a flow of large capacity in the tubing although the length of stroke may be short, and it is contemplated that a pump of this nature may be operated by devices having only a short period of movement 25 and thus overcome the usual objection to the short stroke type of pump and enable the operator to employ means for operating which are otherwise unavailable. My invention is not confined to the double action 30 feature.

The advantages of this type of construction will be obvious to those skilled in the art.

What I claim as new and desire to protect by Letters Patent is:

1. A multiple stage pump including a tubing, a plurality of pump barrels, coupling heads connecting said tubing and said pump barrels together in series, said heads having 40 two longitudinal passages therethrough, a pump rod, pistons in said pump barrels, outlet tubes slideable in said passages and connected to said pump rod and said pistons, inwardly opening valves at each end of said 45 pump barrels, said tubes being provided with openings to allow access of fluid thereto from said pump barrels, the openings in one tube being above said pistons and the openings in the other being below said pistons, and valves at the upper ends of said tubes.

2. A multiple stage pump including a tubing, a plurality of superposed pump barrels, coupling heads connecting said tubing and said pump barrels together in series, pistons in each of said pump barrels, outlet tubes slideable through said coupling heads and connected with said pistons, inlet valves at each end of said pump barrels, means to reciprocate said tubes and said pistons, one of said tubes having openings in said pump barrels above said piston, the other having inlet openings below said pistons, and means to prevent a back flow of fluid through said tubes.

3. A multiple stage pump including a tubing, a plurality of superposed pump barrels, coupling heads connecting said tubing and said pump barrels together in series, pistons in each of said pump barrels, an outlet tube slideable in said coupling heads and connected with said pistons, an upwardly opening valve at the upper end of said tube, and valves allowing entrance of fluid to said pump barrels above said pistons, said tube having inlets above said pistons in the manner described.

4. A multiple stage pump including a tubing, a plurality of pump barrels connected in series at the lower end thereof, coupling blocks connecting said tubing and said barrels and acting to close the ends of said barrels, pistons in said barrels, a tube connecting said pistons, means to reciprocate said tube, means allowing access of fluid from said pump barrels to said tube above said pistons and an upwardly opening valve in said tube.

5. A multiple stage pump including, a tubing, a plurality of pump barrels, coupling blocks connecting said barrels and closing the ends thereof, the upper block being secured to said tubing, pistons in said barrels, two tubes slideable in said blocks and connecting said pistons, means to reciprocate said tubes and pistons, valves in said tubes and means to allow entrance to one of said tubes above said pistons, and similar means allowing entrance of fluid to the other tube from below said pistons.

6. A multiple stage pump comprising a tubing, a plurality of pump barrels connected in series to the lower end thereof, coupling blocks between said barrels, standing valves at both ends of each of said barrels, pistons in said pump barrels, two tubes connected with said pistons and having openings therein to allow entrance of fluid into one of said tubes on the down stroke of said pistons and into the other tube on the up stroke thereof, means to reciprocate said piston and means to prevent the passage of liquid downwardly in said tubes from the upper end thereof.

7. A multiple stage pump including a tubing, a plurality of pump barrels connected in series to the lower end thereof, coupling blocks connecting said tubing and said barrels and acting to close the lower ends of said barrels, standing valves in said barrels, pistons in said barrels, a pair of tubes connecting said pistons and slideable in said blocks, and means to prevent passage downwardly of liquid in said tubes from their upper ends, said tubes having openings thereto below 125 said pistons.

In testimony whereof I hereunto affix my signature this 12th day of March A. D. 1926.

WILLIAM WERNER.
